UNITED STATES PATENT OFFICE

FRITZ A. ANDERSON, OF MILTON, WISCONSIN, ASSIGNOR TO THE BURDICK CORPORATION, OF MILTON, WISCONSIN, A CORPORATION OF DELAWARE

DESIGN FOR A TABLE THERAPEUTIC LAMP

Application filed August 26, 1929. Serial No. 32,543. Term of patent 7 years.

To all whom it may concern:

Be it known that I, FRITZ A. ANDERSON, a citizen of the United States, residing at Milton, in the county of Rock and State of Wisconsin, have invented a new, original, and ornamental Design for a Table Therapeutic Lamp, of which the following is a specification, reference being had to the accompanying drawing forming part thereof.

Fig. 1 is a perspective view of a table therapeutic lamp showing my new design.

Fig. 2 is a plan sectional view of the base taken on the line 2—2 of Fig. 1.

I claim:

The ornamental design for a table therapeutic lamp, as shown.

In witness whereof, I hereunto subscribe my name, this 12th day of August, 1929.

FRITZ A. ANDERSON.
